CLAIM

The ornamental design for a display, as shown and
described.

DESCRIPTION

FIG. 1 is a perspective view of a first embodiment of a
display showing our new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a partially enlarged front elevational view thereof
along the line 6-6 of FIG. 2;

FIG. 7 is a cross sectional view thereof cut along the line 7-7
of FIG. 3; and

FIG. 8 is a cross sectional view thereof cut along the line 8-8
of FIG. 3 wherein internal structure thereof is omitted.

FIG. 9 is a perspective view of a second embodiment of a
display showing our new design;

FIG. 10 is a front elevational view thereof;

FIG. 11 is a rear elevational view thereof;

FIG. 12 is a left side elevational view thereof;

FIG. 13 is a right side elevational view thereof;

FIG. 14 is a partially enlarged front elevational view thereof
along the line 14-14 of FIG. 10;

FIG. 15 is a cross sectional view thereof cut along the line
15-15 of FIG. 11; and,

FIG. 16 is a cross sectional view thereof cut along the line
16-16 of FIG. 11 wherein internal structure thereof is
omitted.

The broken lines illustrating the unclaimed portions of the
display form no part of the claimed design. Dot-dash broken
lines defining the boundaries of the claimed design form no
part of the claimed design.

1 Claim, 14 Drawing Sheets
